CONTROL FOR OIL BURNERS

James L. Breese, Santa Fe, N. Mex., assignor, by
mesne assignments, to Breese Burners, Inc.,
Santa Fe, N. Mex., a corporation of Delaware

Application November 13, 1944, Serial No. 563,195

3 Claims. (Cl. 137—21)

1
My invention relates to an improvement in controls and has for one purpose to provide a control adaptable for use with liquid fuel burners.

Another purpose is to provide means for simultaneously controlling the flow of liquid fuel to an oil burner and the flow of air for combustion, to the burner.

Another purpose is to provide means for delivering a large volume of air to the burner while the burner is warming up, while holding the oil at pilot flow.

Other purposes will appear from time to time in the course of the specification and claims.

The invention is illustrated more or less diagrammatically in the accompanying drawings, 15 wherein:

Figure 1 is an end view with parts broken away;
Figure 2 is a plan view;

Figure 3 is a plan view with the upper portion of the control removed;

Figure 4 is a vertical section through the upper portion of the control;

Figure 5 is a section on the line 5—5 of Figure 4; and

Figure 6 is a section through a burner illustrating the control in side elevation.

Like parts are indicated by like symbols throughout the specification and drawings.

Referring to the drawings 1 indicates an outer housing or drum having an upper portion 2 adapted to serve as a combustion chamber and heat radiating member. The drum may be supported on a plurality of feet 3 having spaces 4 therebetween to admit air. 5 is a horizontal partition having a central aperture 6. 7 is a burner pot shown as having an upper flange 8 resting upon a ring 9 in the drum. The pot is shown as having a plurality of primary air inlets 10 located at various levels and an upper row of secondary air inlets 11. 12 is any suitable centrally apertured flame ring. The bottom of the pot is indicated as at 13. Aligned with the bottom of the pot is a fan 14 adapted to be rotated by any suitable motor 15 mounted on a plate or support 16 shown as secured to the partition 5. 17 indicates any suitable conductive connections for the fan. 20 generally indicates any suitable float valve assembly, the details which of themselves do not form part of the present invention. It may include a float 21 responsive to the level of fuel within the housing 20 and controlling any suitable inflow valve structure, generally indicated at 21a, controlling the supply of liquid fuel to the float chamber or housing 20 along the duct 20a. 22 is any suitable supplemental or safety float, con-

2
trolling a valve actuating lever 23. 24 is an external knob or control element adapted to control the rate of liquid fuel along the duct 25 from the interior of the float chamber 20 to the bottom 13 of the pot 7. 26 is an independent valve actuating element or button, adapted independently to control the valve structure, not herein shown in detail, which controls the rate of liquid fuel along the duct 25 to the burner. 27 is a lever adapted to actuate the button 26. 28 is the lower portion of a control housing removably mounted on the exterior of the top 29 of the float chamber for example by any suitable screws 30. The top of the housing 28 may be enclosed by the upper housing member 31 which may be removably held in position by the screws 32 with upper knurled ends 33. The housing 31 includes a top portion 34 in which is mounted any suitable rheostat coil 35. 36 is a rotatably mounted rheostat contact in the form 20 of a spring arm. It is rotatable for example by the external knob 37, with any suitable pointer 38 which may be rotated about any suitable scale or calibration 39 position upon the top 34 of the housing 31. The rheostat 35 is in circuit, through 25 any suitable conductive connections 17, with the motor 15 and with any suitable outside source of electric power not herein shown. The spring contact 36 is actually mounted on the insulating sleeve or hub 40 which has a central downward socket 41 surrounding the screw end 42. It will be understood that the socket and screw are so formed as to prevent relative rotation of the two. Thus as the knob 37 is rotated the screw 42 is 30 also rotated. The screw is rotatable in the plate 43 which in turn is mounted on brackets 44 upon the bottom of the housing 28. The lever 27 is 35 adapted to be engaged by the actuating knob 45 on the bottom of the screw 42. It will be understood therefore that as the knob 37 is rotated 40 the knob 45 is raised or lowered. The lever 27 is spring thrust upwardly against the knob 45 as by the spring 46 on the screw 47 which extends downwardly from the plate 43 and penetrates an aperture 48 in the lever 27. The inner end of the lever 27 abuts against the adjustable wire 50 one 45 end of which is pivoted at 51 to the plate 43, the other end of which extends to the slot 52 in one side of the lower housing 28, shown for example in Figure 1. The wire 50 has, adjacent the slot 52, a bent end 53 which can be reached, through the slot 52, for example by the end of a tool or wire. Thus the wire 50 can be adjusted, through the slot 52, but cannot be unintentionally moved. It will be understood that as the wire is moved, 55 the distance between that portion of the wire 50

which serves as a pivot for the lever 27 is moved toward and away from the knob 45. This changes the pivot of the lever, and thus the travel of the lever 27 in response to a given rotation of the knob. This thus controls the movement of the valve controlling button 26 in response to rotation of the exterior rheostat controlling knob 31. I may provide any suitable louvres 60 to permit air to circulate through the housing formed by the members 38 and 41.

It will be realized that, whereas, I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

The use and operation of the invention are as follows:

My control is shown as used in connection with a liquid fuel burner in which the liquid fuel is controllably supplied to the burner and in which the rate of air flow to the burner is controlled in relation to variations in the rate of liquid fuel flow to the burner. This combined control is obtained by the employment of a single control knob 31 which actuates at the same time the rheostat contact 36 which controls the air supplying motor, and the valve controlling lever 27. The parts are so proportioned that when the lever 27 moves from low fire toward or to high fire position, the resistance of the rheostat in the motor circuit is reduced and the speed of the motor 15 is correspondingly increased, causing the air flow produced by the fan 14 to increase progressively as the rate of fuel flow is increased. Similarly, the fan speed is decreased as the rate of flow of fuel to the burner along the duct 25 is decreased. As the control box 28, 31, and its contents, may be applied to different sizes and types of float valve control, it is important that the travel of the valve controlling lever 27 be adjusted to suit the particular float valve assembly to which the control box is applied. It is customary in such float valve assemblies to provide an upwardly extending valve controlling button or abutment, such as is shown at 26. But the travel of the button may vary in different types, makes or sizes of float valve assemblies. I therefore provide efficient means for varying the travel of the lever 27, and thus of the valve control button element 26, in response to a predetermined movement of the knob 31 and of the rheostat contact 36 in relation to the rheostat resistance or coil 35. I obtain this result by providing a movable lever pivot in the form of the wire 50 which is pivoted at one end and which has its opposite free end, with its bend 53, aligned with a slot in the side wall of the control box member 28. Thus the device may readily be set, by inserting a wire or point through the slot, but it cannot readily be unintentionally moved. For example, in any particular float valve assembly, it is desirable that a movement of the pointer 38 from zero, in Figure 2, to 100, be accompanied by a progressive movement of the lever 27. If zero indicates minimum rheostat resistance then, when the parts are in the position shown in Figure 2, the lever 27 is raised to the maximum fuel flow position. But as the pointer 38 is moved to the maximum resistance position, cutting the entire rheostat coil into the motor circuit, then the lever 27 is

progressively moved, by rotation of the knob 31, to the low flow or fully depressed position in which the valve control element 26 is moved to reduce the fuel flow to the minimum or pilot rate.

It will be understood that any suitable means may be employed for switching or shorting out the rheostat, when the burner is being started. I do not illustrate such a switch since it does of itself form no part of the present invention. However, in starting with a cold burner it may be desirable to turn the knob 38 to the fuel flow position to provide a sufficient initial supply of liquid fuel in the burner or pot. This involves also turning the rheostat up to full. After the burner is lighted, and during burning off the initial supply of fuel the knob 31 may be turned back to the low flow position. However at that time a large, or maximum supply of air may be desirable, in order to burn off the excess fuel. Any suitable switch means may be provided for, shorting or switching out the rheostat until the pot or burner is ready for normal operation. Thereafter the relation between the rheostat and the valve control is as shown herein and described above. Such a switch means may be manually operated.

I claim:

1. In a control device for liquid fuel burners, a chamber, a delivery duct extending therefrom, means for controllably varying the rate of flow of liquid fuel from the chamber along said delivery duct, including a manually operable valve control, an additional and independently operable valve control for varying said rate of flow, a rheostat including a coil and a movable contact therefor, unitary means for actuating said independent valve control and said rheostat contact, including a manual control element, an actuating connection between it and the rheostat contact, a valve actuating lever and an actuating connection between said lever and said manual control element, and means for varying the effective travel of said lever in response to a predetermined movement of said manual control element, including an abutment, yielding means for normally urging said lever toward said abutment, a pivot element interposed between said lever and said abutment, and means for moving said pivot element.

2. In a control device for liquid fuel burners, a chamber, a delivery duct extending therefrom, means for controllably varying the rate of flow of liquid fuel from the chamber along said delivery duct, including a manually operable valve control, an additional and independently operable valve control for varying said rate of flow, said independent valve control including a valve operating abutment, a control lever adapted for operating engagement with said abutment, a rheostat including a coil and a movable contact therefor, means for simultaneously moving said rheostat contact and said control lever, including a manual handle, a hub, movable unitarily therewith, on which the rheostat contact is mounted, an abutment in which a screw threaded element is rotatably positioned, said element being free to move axially in relation to said hub but interpenetrating therewith in rotation preventing relationship, and an actuating connection between said screw threaded element and said control lever.

3. In a control device for liquid fuel burners, a chamber, a delivery duct extending therefrom, means for controllably varying the rate of flow of

liquid fuel from the chamber along said delivery duct, including a manually operable valve control, an additional and independently operable valve control for varying said rate of flow, said independent valve control including a valve operating abutment, a control lever adapted for operating engagement with said abutment, a rheostat including a coil and a movable contact therefor, means for simultaneously moving said rheostat contact and said control lever, including a manual handle, a hub, movable unitarily therewith, on which the rheostat contact is mounted, an abutment in which a screw threaded element is rotatably positioned, said element being free to move axially in relation to said hub but interpenetrating therewith in rotation preventing relationship, an actuating connection between said screw threaded element and said control lever, and means for varying the pivot point of said lever and for thereby varying the movement of

5

said lever in response to a predetermined rotation of said screw threaded element.
